CLAIM

The ornamental design for a beverage can holder, as shown and described.

DESCRIPTION

This application incorporates by reference U.S. patent application Ser. No. 12/103,545. All the material from application Ser. No. 12/103,545 which is essential to the claimed design is included in this application. Any material in application Ser. No. 12/103,545 that is not present herein forms no part of the claimed design.

FIG. 1 is a perspective view of a beverage can holder showing my new design;

FIG. 2 is side elevation view thereof;

FIG. 3 is a top plan view thereof;

FIG. 4 is a front elevation view thereof, taken from the right as viewed in FIG. 2;

FIG. 5 is a rear elevation view thereof, taken from the left as viewed in FIG. 2; and,

FIG. 6 is a bottom plan view thereof.
